UNITED STATES PATENT OFFICE.

JOSEF HÜBNER AND ISIDOR MAYER, OF VIENNA, AUSTRIA-HUNGARY.

PRESSURE-REDUCING VALVE.

No. 847,944.

Specification of Letters Patent.

Patented March 19, 1907.

Application filed February 19, 1906. Serial No. 301,917.

To all whom it may concern:

Be it known that we, JOSEF HÜBNER and ISIDOR MAYER, both subjects of the Emperor of Austria-Hungary, and residing at Muth-
5 jasse 64, (Waatbahnhof-Heiligenstaat,) Vienna, Austria-Hungary, have invented cer-
tain new and useful Improvements in Pres-
sure-Reducing Valves; and we do hereby de-
clare the following to be a full, clear, and ex-
10 act description of the invention, such as will
enable others skilled in the art to which it
appertains to make and use the same.

Pressure-reducing valves with throttling
15 devices actuated by means of adjustably
weighted or loaded diaphragms or pistons
have the disadvantage that the adjusted low-
pressure is not maintained constant during
working, as with these valves the pressure
falls as the consumption of steam increases.
20 The cause of this deficiency is, on the one
hand, that the load alters or slackens when
the valves are opened and, on the other hand,
that an expansion of the diaphragm occurs
which increases with the stroke of the valve
25 and must be overcome by the loading. More-
over, the high-pressure steam flowing into
the low-pressure chamber causes an increase
of pressure which becomes greater with in-
creased consumption and extends to below
30 the diaphragm or piston. Hereby also the
diaphragms or pistons are prevented from
opening the throttling devices connected
with them to an extent corresponding to the
consumption. The present invention obvi-
35 ates this defect in pressure-reducing valves
and enables them in all cases, even to the
largest consumption of steam, to open a pas-
sage to the inflowing pressure medium neces-
sary for maintaining the adjusted low pres-
40 sure.

The device consists, substantially, of a suc-
tion-nozzle arranged in the low-pressure
chamber of the valve and on which a suc-
tional action is exercised by the high-pres-
45 sure steam flowing into the low-pressure
chamber or the low-pressure steam flowing
away, this suctional effect extending through
a connecting-passage to the under surface of
the diaphragm or piston and in consequence
50 of the powerful suctional action on these
parts, which corresponds to the consumption,
assists or replaces the loading thereof.

In the accompanying drawing three pres-
sure-reducing valves of different and known
55 kinds which are furnished with the suction-

nozzle arranged according to this invention
are shown in sectional elevation.

Figure 1 represents a pressure-reducing
valve the throttling device of which is in the
form of a double-seated valve and is connect-
ed with a spring-loaded diaphragm *b*. The
space *c* below the diaphragm is connected, by
means of a passage *d*, with the suction-nozzle
e, arranged in the low-pressure chamber.
The action of this device will be seen at once
from the drawing.

By the arrangement of the suction-nozzle *e*
a suctional action is produced which increases
with increasing consumption and is caused by
the low-pressure steam flowing past. This
action extends through the connection *d* to the
space *c*. Hereby a reduction of pressure is
produced in that space, so that the dia-
phragm, which is now partially relieved, can
fall with the valve attached to it without
hindrance and open the requisite passage.

In Fig. 2 a piston *b* instead of the dia-
phragm is connected with the double-seated
throttle-valve. In this form of the inven-
tion the connection *d* is placed in a spindle of
80 the valve *a*, which for this purpose is formed
with a boring which likewise contains the
suction-nozzle *e*, that opens into the low-
pressure chamber. The suction-nozzle is so
constructed that partially-exhausted high-
85 pressure steam conveyed into the suction-
nozzle at *e* comes into action.

In Fig. 3 the piston is connected with an
auxiliary valve 1, and this valve with a single,
seat principal valve 2, which can be relieved
90 by pressure beneath 3, and the action of
which is known. The single-seated valve-
cone carries a piston 4, above which during
the taking of steam through the opened aux-
iliary valve 1 the high-pressure steam enters
95 and relieves the principal valve. From this
space a portion of the steam flows through
the suction-nozzle to the low-pressure cham-
ber and produces the necessary reduction of
pressure in the chamber *c*. The pistons of
100 these valves can be loaded either by springs,
throttled steam, or in any other known man-
ner. Beneath the piston or diaphragm the
high-pressure steam flowing in always causes
a certain increase of pressure which prevents
105 the opening of the valve and leads to the fall-
ing of the adjusted low pressure.

By the suctional action of the device which
corresponds to the consumption at any time
not only is the objectionable high pressure in
110

the chamber *c* avoided, but, if necessary, the diminishing loading also supplemented.

What we claim, and desire to secure by Letters Patent, is—

- 5 1. A pressure-reducing valve having a loaded throttling element provided with a fluid-pressure-actuated element, a suction-chamber in which said fluid-pressure-actuated element operates, a high-pressure chamber, a low-pressure chamber communicating therewith, and a suction-duct leading from the suction-chamber to the low-pressure chamber, for the purpose set forth.
- 10 2. A pressure-reducing valve having a loaded throttling element provided with a fluid-pressure-actuated element, a suction-

chamber in which said fluid-pressure-actuated element operates, a high-pressure chamber, a low-pressure chamber communicating therewith, a suction-duct leading from the suction-chamber and a suction-nozzle forming the discharge end of said duct and discharging into the low-pressure chamber, for the purpose set forth.

In testimony whereof we have affixed our signatures in presence of two witnesses.

JOSEF HÜBNER.
ISIDOR MAYER.
